[57]**CLAIM**

The ornamental design for a housing for a scanning, faxing and printing machine, as shown.

DESCRIPTION

FIG. 1 is a frontal perspective view of an housing for a scanning, faxing and printing machine showing my new design;

FIG. 2 is a front view;

FIG. 3 is a left side view;

FIG. 4 is a right side view;

FIG. 5 is a rear view;

FIG. 6 is a top view;

FIG. 7 is a reduced bottom plan view; and,

FIG. 8 is a reduced perspective view from the top, rear and one side.
